Primary Examiner — T. Chase Nelson(74) *Attorney, Agent, or Firm* — Andrew F. Young, Esq.; Lackenbach Siegel, LLP(57) **CLAIM**

The ornamental design for a shoe sole, as shown and described.

DESCRIPTION

FIG. 1 is a front perspective of a shoe sole.

FIG. 2 is a right side elevational view of the shoe sole of FIG. 1.

FIG. 3 is a left side elevational view of the shoe sole of FIG. 1.

FIG. 4 is a front elevational view of the shoe sole of FIG. 1. FIG. 5 is a rear elevational view of the shoe sole of FIG. 1; and,

FIG. 6 is a bottom view of the shoe sole of FIG. 1.

The broken line showing of portions of the shoe sole, as well as of the shoe, are for purposes of illustrating environmental structure and portions of the shoe sole that form no part of the claimed design.

1 Claim, 5 Drawing Sheets# US D677,867 S
